E. CAVIGELLI,
MACHINE FOR MAKING TULLE,
APPLICATION FILED MAR. 25, 1921.

1,404,373.

Patented Jan. 24, 1922.

UNITED STATES PATENT OFFICE.

EMANUEL CAVIGELLI, OF ST. MARGARETHEN, NEAR MÜNCHWILEN, SWITZERLAND,
ASSIGNOR TO THE FIRM SCHWEIZ, GESELLSCHAFT FÜR TÜLLINDUSTRIE A.-G., OF
MÜNCHWILEN, SWITZERLAND.

MACHINE FOR MAKING TULLE.

1,404,373.

Specification of Letters Patent. Patented Jan. 24, 1922.

Application filed March 25, 1921. Serial No. 455,514.

(GRANTED UNDER THE PROVISIONS OF THE ACT OF MARCH 3, 1921, 41 STAT. L., 1313.)

To all whom it may concern:

Be it known that I, EMANUEL CAVIGELLI, a citizen of the Republic of Switzerland, residing at St. Margarethen, near Münchwilen, Thurgau, Switzerland, have invented certain new and useful Improvements in Machines for Making Tulle (for which applications for patent have been filed in Switzerland, Nov. 22, 1919, Patent No. 88,739; Germany, December 4, 1919, application No. 56,888; England, November 22, 1920, appln. No. 32,928/1920, and France, January 5, 1921, appln. No. 138/296;) and I do hereby declare the following to be a clear, full, and exact description of the invention, such as will enable others skilled in the art to which it appertains to make and use the same, reference being had to the accompanying drawings, and to letters or figures of reference marked thereon, which form a part of this specification.

This invention relates to machines for making tulle or bobbinet and more particularly to a combination warp beam brake for such machines.

The tension of the warp threads in tulle machines is preferably produced by braking the warp beam. As is known, the tension of the weft threads, that is to say, of the diagonal spool threads, continuously increases during the working process, and the tension of the warp threads must be increased to a corresponding extent in order to avoid any deformation of the hexagonal mesh or loop structure. To that end, the band or rope brake with which the existing constructions of tulle machines are provided are in most cases more strongly applied by the hand of the tulle weaver during the working process. Constructions are also already known in which the increase of the braking action of such a brake is automatically produced in dependence on the rotary motion of the warp beam. This brake construction cannot, however, be applied with a satisfactory effect to modern heavy tulle machines, as in the case of unavoidable higher brake pressures in heavy tulle machines the brake devices not only lose their sensitiveness, but fail altogether. The faces of the brake disc become corroded or damaged when steel cables are used. If hemp

ropes are used, the braking is affected by the influences of the different heat and moisture conditions. In both cases the action is exceedingly injurious to the nature of the fabric produced.

This invention relates to a brake device for the warp beam, in which the above mentioned drawbacks are avoided.

According to this invention a combination brake is provided which comprises a braking means by which the normal tension of the warp threads is produced at the beginning of the working and maintained constant during the whole working period, and additional braking means which produce an additional braking action increasing during the working process and derived from the rotary motion of the machine.

A construction according to the invention is illustrated by way of example in the accompanying drawings. In the same:

Figure 1 is a side elevation of a tulle-making machine provided with the device.

Figure 2 is a section through the elastic device to which the brake lever is connected.

Figure 3 is a vertical section on the line III—III of Figure 4.

Figure 4 is a side elevation, partly in section on the line IV—IV of Figure 3.

Figure 5 is the plan corresponding to Figures 3 and 4 of the arrangement of the device.

Figure 6 is a horizontal section through the axis of the brake on line VI—VI of Fig. 3.

The working of the device according to the invention will be considered simultaneously with the following description of the single parts of the same.

In Figure 1, 1 indicates the warp threads which are unwound from a warp beam 2, then woven into a fabric by the two wefts, and wound over a suitable breast beam 3 and pressure roller on to a cloth beam in the form of a finished fabric. To the warp beam 2 is firmly secured a brake pulley 4, the rim of which is provided with flanges between which is mounted a brake band 5, one end of which is secured to the machine frame, whilst the other end is secured to a pull rod 6. The rod 6 is provided with a screw thread and can be pulled by hand by

means of a thumb nut 7 which through the intermediary of a spring 8, presses against a support provided on the frame. In that way a braking action can be exercised on the brake pulley 4, and therefore on the warp beam 2. On the inner circumference of the rim of the brake pulley are provided two brake jaws 9 and 9' which are rotatably mounted on a pin 10 secured to the machine frame, and can be pressed against the rim of the pulley by means of a cam 11 arranged diametrically opposite the pivot pin 10 and rotatably mounted on a pin secured to the frame. The cam 11 is turned by means of 10 the brake lever 12 and presses the two brake jaws apart and against the inner face of the pulley rim. Two springs 13 bring about the withdrawal of the brake jaws from the brake pulley and their return to the initial position, when the lever 12 is brought back to 15 its original position at the beginning of the working process. The gradual tightening of the brake lever is brought about by the rotation of a driving shaft 14 in the following manner.

To the shaft 14 is secured a pulley 15 provided with a cam face, which at each revolution acts on a roller 16. The roller 16 is secured in a cranked lever 17 which carries 20 on the other arm a pawl 18 engaging with a ratchet wheel 19.

The ratchet wheel 19 is secured on a spindle 20 on which the lever 17 is mounted so that it can swing on it. The roller 16 is 25 pressed against the pulley 15 by a spring (not shown in the figure) secured to a fixed arm 21, and at each revolution of the shaft 14 owing to the rolling over the cam face, experiences a movement in a plane at right angles to the spindle 20. Owing to this operation, the lever 17 swings about the spindle 20 as its axis of rotation, and the pawl 18 turns the ratchet wheel 19 and the spindle secured to it, to the extent of at least one 30 division. On the spindle 20 which is mounted in the casing of a worm gear 22, 23, is mounted a worm 22 which is in engagement with a worm wheel 23 and further at one end of the spindle there is also provided a crank handle 24 for operating the spindle by hand. The worm wheel is mounted loose on the worm wheel spindle 25 and has on one side of the worm a number (eight in the drawing) of 35 interchangeable bolts 25¹ concentrically screwed in. On the worm wheel spindle 25 is keyed on one side of the worm wheel a ratchet wheel 26 which is driven by a pawl 27. The pawl 27 is mounted on a double-armed lever 28 mounted on a pivot pin on the worm gear casing. The rotation of the spindle 20 is transmitted by the worm 22 to the worm wheel 23. The oscillating movement of the lever is produced by the action 40 of the bolts 25¹ on a cam 29 secured to the

lever 28 owing to which the ratchet wheel is turned by the pawl to the extent of at least one tooth at each passage of one of the bolts 25¹ past the cam 29. By a spring 28¹ secured to the other arm of the lever 28, the latter is pulled back against a stop 28². Another pawl 30 rotatably mounted on the casing, is in engagement with the ratchet wheel 26 for the purpose of preventing the wheel from turning back. At the other end 45 of the worm gear spindle 25 is secured a winch-like spider 31, between the arms of which is mounted a spirally coiled spring blade 32. The inner end of the spring blade or coil is secured to the hub of the spider, the outer end to a traction part 33 which connects the brake lever 12 to the spring 32. The rotation of the ratchet wheel 26 produces therefore a winding of the spring blade 32, owing to which a gradually increasing pull is produced on the 50 brake lever arm, and therefore a constantly increasing braking action.

By changing the number of the bolts provided in the disc of the worm wheel, the gear ratio between the number of revolutions of the driving shaft and the number of revolutions of the spring blade spindle, can be altered, and thus a modification obtained in the increase of the tension of the warp threads. Another method of regulating the gear ratio consists in the adjustment or shifting of the stops of the levers which carry the pawls. In that way it is possible to move the pawls back by the springs on 55 the lever to such an extent that instead of engaging with the next tooth, they engage with the second, third and so on, of the ratchet wheel, and during the next oscillation of the lever would turn the ratchet wheel to the extent of more than one tooth.

The combination of the brake lever with the spring blade has the great advantage of a braking action taking place in a yielding manner, owing to which the variations of the 60 braking action, due to the friction differences in the sliding surfaces, are automatically equalized or compensated.

I claim:

1. An automatic combination warp beam 65 brake for heavy tulle-making machines, comprising braking means operatively connected to the warp beam, and adapted to produce at the beginning of the working period the normal tension of the warp threads and 70 maintain it constant during the whole working period, additional braking means operatively connected to the warp beam and adapted to produce an additional braking action, and means actuated upon the rotation of the driving shaft of the machine 75 adapted to influence said additional braking means for gradually increasing said additional braking action during the working period.

2. An automatic combination warp beam
brake for heavy tulle-making machines, com-
prising a hand operated hand brake opera-
tively connected to the warp beam and
adapted to produce at the beginning of the
working period the normal tension of the
warp threads and maintain it constant dur-
ing the whole working period, a jaw brake
mounted on the brake pulley for the band
brake and adapted to produce an additional
braking action and means actuated upon the
rotation of the driving shaft of the machine,
adapted to influence said jaw brake for grad-
ually increasing said additional braking ac-
tion during the working period. 55
3. An automatic combination warp beam
brake for heavy tulle-making machines, com-
prising a hand operated band brake, the
brake pulley of which being mounted on
the warp beam and adapted to produce at
the beginning of the working period the
normal tension of the warp threads, and
maintain it constant during the whole work-
ing period, a jaw brake mounted on the
brake pulley for the band brake and adapted
to produce an additional braking action, a
brake lever for operating said jaw brake and
a gear interposed between said brake lever
and the driving shaft of the machine adapt-
ed to convert the rotation of the driving
shaft into a pull on said brake lever for in-
creasing said additional braking action by
gradually increasing the movement of said
brake lever with the duration of the working
period. 80
4. An automatic combination warp beam
brake for heavy tulle-making machines, com-
prising a hand operated band brake, the
brake pulley of which being mounted on the
warp beam, and adapted to produce at the
beginning of the working period the normal
tension of the warp threads and maintain it
constant during the whole working period, a
jaw brake mounted on the brake pulley for
the band brake and adapted to produce an
additional braking action, a brake lever for
operating said jaw-brake, a gear interposed
between said brake lever and the driving
shaft of the machine adapted to convert the
rotation of the driving shaft into a pull on
said brake lever for increasing said addi-
tional braking action by gradually increas-
ing the movement of said brake lever with
the duration of the working period, and
means for modifying the ratio of said gear
within wide limits. 105
5. An automatic combination warp beam
brake for heavy tulle-making machines, com-
prising a hand operated band brake, the
brake pulley of which being mounted on the
warp beam, and adapted to produce at the
beginning of the working period the normal
tension of the warp threads and maintain
it constant during the whole working pe-
riod, a jaw brake mounted on the brake pul-
ley for the band brake and adapted to pro-
duce an additional braking action, a brake
lever for operating said jaw brake, a spring
blade spiral the outer end of which being
operatively connected to said brake lever 70
the inner end being secured to a spindle,
gear means interposed between said spindle
and the driving shaft of the machine and
adapted to impart rotation of said spindle
for winding said spring blade spiral on its
spindle and thus exerting a pull on said
brake lever for increasing said additional
braking action by gradually increasing the
movement of said brake lever with the dura-
tion of the working period. 75
6. An automatic combination warp beam
brake for heavy tulle-making machines, com-
prising a hand operated band brake, the
brake pulley of which being mounted on the
warp beam, and adapted to produce at the
beginning of the working period the normal
tension of the warp threads, and maintain it
constant during the whole working period, a
jaw brake mounted on the brake pulley for
the band brake and adapted to produce an
additional braking action, a brake lever for
operating said jaw brake, a spring blade
spiral the outer end of which being opera-
tively connected to said brake lever the inner
end being secured to a spindle, gear means 90
interposed between said spindle and the
driving shaft of the machine and adapted to
impart rotation of said spindle for winding
said spring blade spiral on its spindle and
thus exerting a pull on said brake lever for
increasing said additional braking action by
gradually increasing the movement of said
brake lever with the duration of the working
period, and means for modifying the ratio
of said gear within wide limits. 95

In testimony that I claim the foregoing as
my invention, I have signed my name.

EMANUEL CAVIGELLI.
